US00D586814S

(12) **United States Design Patent**
Kramer et al.

(10) **Patent No.:** **US D586,814 S**
(45) **Date of Patent:** **** Feb. 17, 2009**

(54) **INFORMATION HANDLING SYSTEM
POWER SUPPLY HANDLE**

(75) Inventors: **Paul Kramer**, Austin, TX (US);
Richard Crisp, Austin, TX (US);
Vincent Lam, Austin, TX (US)

(73) Assignee: **Dell Products L.P.**, Round Rock, TX (US)

(**) Term: **14 Years**

(21) Appl. No.: **29/275,827**

(22) Filed: **Jan. 8, 2007**

(51) **LOC (9) Cl.** **14-02**

(52) **U.S. Cl.** **D14/432**

(58) **Field of Classification Search** D14/300–302,

(57) **CLAIM**

The ornamental design for an information handling system power supply handle, as shown and described.

DESCRIPTION

FIG. 1 is a front perspective view of the information handling system power supply handle comprising the present invention;

FIG. 2 is a top view thereof;

FIG. 3 is a front view thereof;

FIG. 4 is a left side view thereof; and,

FIG. 5 is a right side view thereof.

The broken line showing of portions of the information handling system power supply handle is included for the purpose of illustrating environmental structure and forms no part of the claimed design.
